UNITED STATES PATENT OFFICE.

JAMES RHODES WERTH, OF RICHMOND, VIRGINIA.

SPARK-ARRESTER.

SPECIFICATION forming part of Letters Patent No. 309,014, dated December 9, 1884.

Application filed April 12, 1884 (No model.)

To all whom it may concern:

Be it known that I, JAMES R. WERTH, of Richmond, in the county of Henrico and State of Virginia, have invented certain new and 5 useful Improvements in Spark-Arresters, of which the following is a full, clear, and exact description.

My invention relates to improvements in spark-arresters; and it consists in the peculiar 10 construction and arrangement of parts, as hereinafter fully described, and pointed out in the claims.

Reference is to be had to the accompanying drawings, forming a part of this specification, 15 in which similar letters of reference indicate corresponding parts in all the figures.

Figure 1 represents a vertical longitudinal section of a locomotive-engine boiler embodying my invention; Fig. 2, a vertical section 20 of the smoke-stack, in part, with the portion of the invention that pertains thereto applied; and Fig. 3, an under view of the deflector. Figs. 2 and 3 are upon a larger scale than Fig. 1.

A is the fire-box, and B the smoke-box, of 25 the boiler; C, the body, and D D the smoke-flues.

E is a combustion chamber, arranged between the fire box and smoke-box flue-sheets, beneath the dome F. This construction necessitates the use of two sets of smoke-flues, D D, one set connecting the fire-box with the combustion-chamber, and the other set connecting the combustion-chamber with the smoke-box, each set consequently being less 30 than one-half the usual length of the flues. The combustion-chamber E has a man-hole in its top, closed by a lid, to admit a workman within said chamber to fasten the flues D D to the flue-sheets of the chamber.

40 G is the smoke-stack, mounted with the usual head or cap, G'. Within this cap G', at or near its top, is a hood or deflector, H, arranged immediately over a funnel, I, on the top of a spark-return tube, J, and constructed to turn 45 the sparks received up within it from outside of the funnel toward its center and down into the funnel I. Connecting this deflector H with the lower end portion of the head or cap G', and in continuation, or nearly so, as 50 it were, with the smoke-stack G, is an upright cylindrical netting, K, within the head or cap

G'. The under side of the deflector H has an annular groove, b, in it to receive the upper end of the netting K, and has its interior cup-like deflecting surface divided by any number 55 of thin radial partitions, c, cast solid with it, and the upper end of the funnel I is provided with lateral projections, which enter within cut-away portions of the inner lip of the groove, opposite or over any number of stud-bolts, d, 60 which serve to support and carry the deflector with its entered netting and the funnel, said studs passing from the smoke-stack up to and through the deflector, and being provided with eccentric collars e, to bind on bands, which 65 pinch or hold the netting. These studs are much the same as are used in holding cones in diamond stacks.

The object of placing the netting K vertical is to deflect the sparks into the deflector H, 70 and from thence into the funnel I. From the funnel I the deflected sparks may be conveyed by the pipes J J' into a spark-chamber, L, on the forward part of the engine, and from thence by pipes within or outside of the fire-box A, 75 or to the combustion-chamber E; or the sparks collected within the chamber L may be otherwise removed, or they may be conveyed by the pipe J either into the smoke-combustion chamber E or into the fire-box A, which latter would 80 be the case where no intermediate combustion-chamber is used, said pipe J, which may be a simple boiler-tube, passing along within the boiler; or said sparks may be conveyed by an outside pipe, J', to the fire-box. The movement or passage of the sparks may be accelerated 85 through the pipes J J' by air or steam jets or jet-pipes f, that may be provided with regulating-valves under the control of the engineer, such jets generally, however, only being necessary when the pressure under the deflector and the partial vacuum in the fire-box are insufficient to secure the rapid return of the sparks.

From the foregoing description, it will be 95 seen that no attempt is made to separate the smoke from the sparks until after the mingling of the same with the exhaust-steam, no separation taking place in the smoke-box. Furthermore, as the deflector H is above the netting K and at the top or above the smoke-stack, no separation can take place below the net-

ting and above the exhaust-nozzle; and as there are no deflectors or obstructions between the tube sheet of the boiler and the netting, I succeed in utilizing the full effect of the blast. 5 Again, even still more dissimilar is my arrangement from those which provide for the escape of the exhaust-steam into the air without passing through a netting, and only mingles with such sparks as have escaped through 10 the netting.

By my improved construction and arrangement of parts for catching the sparks, I am enabled to use a finer netting than is ordinarily employed—first, because a greater area 15 of netting-surface is obtained by reason of the cylindrical shape of the netting, and, secondly, because the plane in which the netting lies is not at right angles to the blast, as is usually the case, but is vertical and parallel with the 20 line of the blast; consequently the lodgment of sparks on the netting is next to impossible, inasmuch as the netting will be swept clean of all particles of unconsumed coal at or by each escape of the exhaust, and said particles, being 25 caught in the funnel, cannot subject the gauze to repeated abrasion, or, in case of the priming of the boiler, stop up the meshes of the netting. While, therefore, by the increased area of openings for the escape of 30 smoke which my arrangement secures, a finer mesh may be used, if preferred, this is not absolutely necessary, as, the direction of the blast and course of the flying cinders or particles being parallel with the cylindrical netting, a 35 coarser gauze may be used, inasmuch as the cinders or floating particles of burning fuel must be deflected from their course and strike the gauze at an oblique angle, which will insure the abrasion of the spark before escaping.

M is a pipe for admitting air to the combustion-chamber E, to assist in consuming the waste gases. This pipe connects at its receiving end with an annular space, g, outside of the smoke-stack, and is formed by said smoke-stack and a surrounding pipe or jacket, N, 45 which is provided with a series of perforations, h, for the admission of air.

Having thus fully described my invention, I claim as new, and desire to secure by Letters Patent—

1. The combination, with the smoke-stack G, provided with the wire netting K, and the deflector H, of the chamber L on the forward part of the engine, the funnel I, arranged under the deflector, the pipe J, extending down the center of the stack, and branch pipe J², leading to the said chamber L, substantially as herein shown and described.

2. The combination, with the smoke-stack G, of the deflector H, having the annular 60 groove b, the wire netting K, the funnel I, and the bolts d, substantially as herein shown and described.

3. The combination, with the smoke-stack G, the funnel I, the screen K, and the bolts d, 65 of the deflector H, provided with the radial partitions e, substantially as herein shown and described.

4. The combination, with the smoke-stack G, the deflector H, the funnel I, and the screen 70 K, of the bolts d, provided with the eccentric collars e, substantially as herein shown and described.

JAMES RHODES WERTH.
